UNITED STATES PATENT OFFICE.

COLUMBUS HOUCK BISHOP, OF EL RENO, OKLAHOMA.

CAR-GEAR EQUIPMENT.

1,110,871.

Specification of Letters Patent. Patented Sept. 15, 1914.

Application filed September 25, 1913. Serial No. 791,767.

To all whom it may concern:

Be it known that I, COLUMBUS HOUCK BISHOP, a citizen of the United States, and a resident of El Reno, county of Canadian, 5 and State of Oklahoma, have made certain new and useful Improvements in Car-Gear Equipments, of which the following is a specification.

My invention is an improvement in car 10 gear equipments, and has for its object to provide mechanism for connection with the body of a railroad car, for causing the brakes to be applied when pressure is exerted on the couplings of the car, wherein 15 draw bars or coupling bars are provided, mounted to slide on the car body, each of the said bars bearing at its outer end a coupling head, and having mechanism for engaging the brake mechanism of the adjacent 20 truck for applying the brakes, when the coupling bar is moved inward, and wherein spring mechanism is provided for normally pressing the coupling bars outward.

A further object is to provide mechanism 25 in connection with the coupling bars, for locking the brakes in set position.

In the drawings: Figure 1 is a top plan view of the base frame of the equipment, Fig. 2 is a side view of the same, Figs. 3 and 30 5 are sections on the lines 3-3 and 5-5 respectively, of Fig. 1, Fig. 5 looking in the direction of the arrows, with parts broken away in Fig. 5. Fig. 4 is a perspective view of one of the couplings. Fig. 6 is a section 35 on the line 6-6 of Fig. 1, looking in the direction of the arrow, and Fig. 7 is a top plan view of the locking mechanism for holding the brake in set or released position.

The present embodiment of the invention 40 consists of a substantially rectangular open base frame, composed of longitudinally extending side members 1 and connecting end members 2, each of the said members being of channel material, as shown in Figs 3 and 45 5, and arranged with its channel inward. Intermediate the connecting end members, the side members are connected by cross bars 3 on each side of the transverse center of the frame, and by other cross bars 4 adjacent to 50 the end members 2, and by other cross bars 5 adjacent to the cross bars 3.

Oppositely arranged pairs of diagonal braces 6 are arranged between the adjacent cross bars 3 and 5, the pairs of braces being

crossed, and one of the pairs being arranged 55 on each side of the longitudinal center of the frame. The bars 3 are connected by cross plates 7 on each side of the longitudinal center of the frame.

The cross plates 7 are arranged in pairs, 60 the members of each pair being parallel and spaced apart vertically from each other. The upper member of each pair has its ends resting upon the upper edges of the cross bars 3, and secured to the said cross bars, 65 while the lower member of each pair is provided at each of its ends with an angular lug 10, for engaging the inner face of the adjacent cross bar, and the lugs are connected to the cross bars by means of rivets or 70 bolts. A bolster 11 is arranged transversely of the frame between each pair of the cross plates 8.

A pair of elliptical springs 12 is arranged between the cross bars 3, the long axis of 75 each spring being transverse to the frame. The adjacent halves or sections of the springs are connected by a coupling 13, and the outer face of the other section or half of each spring is adjacent to one of the cross 80 bars 3, and is connected to a cross head or shoe 14 on the adjacent end of the adjacent coupling bar 15. The shoe 14 of each coupling bar is curved on the face adjacent to the spring to fit the outer face of the 85 adjacent leaf, and each shoe is provided with openings 16 near its ends for receiving bolts or rivets, to connect the shoe to the spring.

Each coupling bar 15 slides through a 90 bearing 17 on the upper face of the adjacent bolster, and each coupling has connected thereto an arc-shaped cross bar 18, the said bar being on the inner side of the inner cross plate of the adjacent pair, and each 95 cross bar is connected to the coupling bar by an arm 19. The cross bars 18 are arranged with their convex surfaces inwardly, and each of the said cross bars is designed to operate the brake of the adjacent truck, 100 when the coupling bar is pressed inwardly. The coupling for the car is connected with the outer end of the coupling bar, and the said coupling may be of any desired character or make. The trucks are pivoted to the 105 car body in a manner to be later described, and the arched form of the cross bar 18 is to permit the cross bar to engage the op-

erating lever regardless of the relative position of the truck and the body.

The wheels 20 are secured to the axles 21 in the usual manner, and the said axles are 5 journaled in bearing blocks 22 which are movable vertically in journal boxes 23. The journal boxes are on both sides of the wheels 20, as shown in Fig. 5, and the said boxes are connected with pedestals 24 arranged 10 transversely of the frame of the car, and connected with each truck in the usual manner, as shown in Fig. 2.

Girders 9 are arranged transversely of the pedestals of each truck near the ends thereof, and the bolsters 11 of the base frame are pivoted to the trucks constituted by the pedestals and their connections in the usual manner, and during the turning of the trucks the bolsters move upon the girders 9 20 before mentioned. The bolsters 11 are transversely grooved on their under faces and near their ends as indicated at 11^a to receive the girders. Two brake shoes 26 and 27 respectively are arranged adjacent to 25 each of the inner wheels of each truck, the said shoes being on opposite sides of the wheel. Two shoes 28 and 29 respectively are arranged adjacent to each of the outer wheels of each truck.

30 The shoes 28 at the outer sides of the trucks are connected to the ends of a rod 28^a. The rod is supported by a lever 29, the lower end of the lever engaging the rod at approximately its center, and the upper 35 end of the lever is pivoted to a bracket arm 30 extending outwardly from the adjacent pedestal on the truck. Each of the shoes 29 is connected to one end of a rod 29^a, and each rod is supported by a lever 31, the lower 40 end of the lever being connected to the rod at approximately its center. Each lever 31 is pivoted intermediate its ends to an arm 32 extending inwardly from the outer pedestal of the truck.

45 The shoes 26 are arranged on the ends of a rod 26^a, and a lever 33 is connected to the rod intermediate its ends. The upper end of the lever 33 is pivoted to a bracket arm 34 extending from the inner pedestal of the 50 truck. The brake shoes 27 are connected to the ends of a rod 27^a, and a lever 35 engages the rod at its lower end, and at approximately the center of the rod. The upper end of the lever 35 is position for engagement by the cross bar 18 of the adjacent coupling bar 15, and a link 36 connects the lever 35 with the upper end of the lever 31.

A link 37 is pivoted at one end to the lever 35 adjacent to the connection of the link 36, 60 and the said link 36 is pivoted at its opposite end to the lever 29 intermediate the ends of the said lever. The link 37 is also pivoted to the lever 33 intermediate the ends of the said lever, and it will be obvious 65 that when the upper end of the lever 35 is

moved inwardly, the eight shoes of the truck will be applied to the wheels. Each of the coupling bars 15 slides in mortises 38 and 39 in the cross bars 3 and 5 at the said end, and each of the said bars is provided with oppositely extending lugs 40 adjacent to the mortises 38, the said lugs being adapted to engage the outer side of the cross bar to limit the inward movement of the coupling bar, and the other pairs of lugs 41 and 42 are 75 arranged on the coupling bar 3, for engaging the said bar, to limit the movement of the coupling bar in each direction. 70

It will be evident that when either of the coupling bars is moved inwardly to compress the springs 12, the brakes at that end of the car adjacent to the coupling bar will be set. The springs 12 cannot swing laterally on account of the guide plates 7, and when either coupling bar is pressed inwardly, the springs 85 will be compressed. 80

Mechanism is also provided for coöperating with the lug 41 and 42 at one side of each coupling bar for holding the brakes operated by the said bar in set or released position. The said mechanism comprises a pair of blocks 43 and 43^a respectively, the said blocks being of a width such that they will be received between a lug or shoulder 41 and the adjacent cross bar 5. 90

Each block is carried on the end of a slide rod 44, and each rod is mounted to slide in bearings 45 on one of the cross bars 5. At its outer end each rod is bent laterally from the cross bar, as shown at 46, and the free 100 end of each of the angular portions is provided with vertically spaced lugs 47. A lever 48 is pivoted in a slot 50 in the cross bar 5, by means of a pivot pin 51, and the said lever is slotted at each of its ends, as 105 indicated at 49. A bolt 52 is passed through each lug and the adjacent slot, for pivotally connecting the angular portion of the rod to the lever.

In operation, the coupling heads are connected with the outer ends of the coupling bars 15, and it will be evident that when the said coupling bars are pressed inwardly, the brakes of the trucks adjacent to the bar will be set. As soon as the pressure is released, 110 the springs 12 will expand, releasing the brakes. When it is desired to fix the brakes in either open or closed position, the lever 48 adjacent to the coupling bar is operated to move one of the blocks 43 and 43^a, as the 115 case may be, inwardly, as shown in Fig. 7. The lever 48 may be operated in any suitable manner, each lever having openings 53 at its ends for connection with suitable operating mechanism. When the coupling bar 120 is pressed inwardly, the block 43^a will fit between one of the shoulders 41 and the cross bar 5, and will hold the coupling bar with the brake set. When the brakes are released, 125 and the coupling bar is in its outermost po- 130

sition, the block 43 may be moving inwardly to a position between the shoulder 42 and the cross bar 5.

I claim:

5. 1. In combination with the body of a car and the trucks at the ends of the body, of coupling bars mounted for sliding movement and in alinement and extending beyond the cars at the ends thereof, said bars being adapted for connection with coupling heads at their outer ends, springs arranged between the inner ends of the bars and normally forcing them away from each other, means in connection with each bar for limiting its movement in either direction, brake mechanism in connection with each truck, a lever at the inner side of each truck for operating the said mechanism, and a cross bar rigid with each coupling bar and below the same, and in position to engage the lever and to operate the same to set the brakes when the coupling bar is moved inwardly, and means in connection with each coupling bar for locking the bar with the brakes in set or released position, each of the said means comprising a pair of slide rods mounted for sliding movement on the frame toward and from the coupling bar, a block at the inner end of each slide rod, each coupling bar having shoulders for engagement by the blocks of the respective rods to hold the bars in inward or outward position, a lever pivoted to the frame at the outer ends of the rods, a pivotal and sliding connection between each lever and the rod, for moving the rod longitudinally when the lever is swung.
2. In combination with the body of a car and the trucks at the ends of the body, of coupling bars mounted for sliding movement and in alinement and extending beyond the cars at the ends thereof, said bars being adapted for connection with coupling heads at their outer ends, springs arranged between the inner ends of the bars and normally forcing them away from each other, means in connection with each bar for limiting its movement in either direction, brake mechanism in connection with each truck, a lever at the inner side of each truck for operating said mechanism and a cross bar rigid with each coupling bar and below the same, and in position to engage the lever and to operate the same to set the brakes when the coupling bar is moved inwardly, and means in connection with each coupling bar for locking the bar with the brakes in set or released position, each of the said means comprising slide rods mounted for sliding movement toward and from the coupling bar, each bar having shoulders for engagement by the inner ends of the rods to hold the bar in inward or outward position, and means for alternately moving the rods in opposite directions.
3. In combination with the body of a car and the trucks at the ends of the body, of coupling bars mounted for sliding movement and in alinement and extending beyond the cars at the end thereof, said bars being adapted for connection with coupling heads at their outer ends, springs arranged between the inner ends of the bars and normally forcing them away from each other, means in connection with each bar for limiting its movement in either direction, brake mechanism in connection with each truck, a lever at the inner side of each truck for operating the said mechanism, and a cross bar rigid with each coupling bar and below the same, and in position to engage the lever and to operate the same to set the brakes when the coupling bar is moved inwardly, and means in connection with each coupling bar for locking the bar with the brakes in set or released position.
4. In combination with the body of a car and the trucks at the ends of the body, of coupling bars mounted for sliding movement and in alinement and extending beyond the cars at the end thereof, said bars being adapted for connection with the coupling heads at their outer ends, springs arranged between the inner ends of the bars and normally forcing them away from each other, means in connection with each bar for limiting its movement in either direction, brake mechanism in connection with each truck, a lever at the inner side of each truck for operating the said mechanism, and a cross bar rigid with each coupling bar and below the same, and in position to engage the lever and to operate the same to set the brakes when the coupling bar is moved inwardly, and means in connection with each coupling bar for locking the bar with the brakes in set or released position.
5. In combination with the body of a car and the trucks at the ends of the body, of coupling bars mounted for sliding movement and in alinement and extending beyond the cars at the end thereof, said bars being adapted for connection with coupling heads at their outer ends, springs arranged between the inner ends of the bars and normally forcing them away from each other, means in connection with each bar for limiting its movement in either direction, brake mechanism in connection with each truck, a lever at the inner side of each truck for operating the said mechanism, and a cross bar rigid with each coupling bar and below the same, and in position to engage the lever and to operate the same to set the brakes when the coupling bar is moved inwardly, and means in connection with each coupling bar for locking the bar with the brakes in set or released position.

coupling bar is moved inwardly, said bars being arched transversely and having their convex faces toward the levers, to permit lateral movement of the lever with respect 5 to the bar without disengagement therefrom.

6. In combination with the body of a car, and the wheels for supporting the same, and the brake mechanism coöperating with the wheels, of a coupling bar at each end of the 10 car, and mounted for sliding movement longitudinally of the frame, springs normally pressing the said bars outward, means for limiting the movement of the bars in each direction, a lever for operating the brake 15 mechanism at each end of the car, and means in connection with each coupling bar for engaging the lever to set the brakes when the bar is moved inwardly, and means in connection with each coupling bar for lock- 20 ing the bar with the brakes set or released.

7. In combination with the body of a car, and the wheels for supporting the same and the brake mechanism coöperating with the

wheels, of a coupling bar at each end of the car and mounted for longitudinal sliding 25 movement with respect to the car, yielding means normally pressing the bars outward away from each other, means in connection with each of the brake mechanisms for engagement by the adjacent coupling bar to 30 operate the said mechanism when the bar is moved inwardly, each coupling bar having a plurality of stops intermediate its ends, and spaced apart from each other longitudinally 35 of the bar, a locking block for each stop, one of the blocks being adapted to engage a stop to hold the bar in inward position and the other block being adapted to engage a stop to hold the bar in outward position, said blocks being mounted for sliding movement 40 toward and from the adjacent bar, and means for alternately moving the blocks.

COLUMBUS HOUCK BISHOP.
